WHEEL FEEDING MECHANISM

Wallace H. Wood, Worcester, Mass., assignor to
Norton Company, Worcester, Mass., a corpora-
tion of Massachusetts

Application November 6, 1936, Serial No. 109,540

7 Claims. (Cl. 51—95)

The invention relates to grinding machines, and more particularly to a grinding wheel feeding mechanism.

One object of the invention is to provide a simple, thoroughly practical grinding machine slide actuating mechanism. Another object of the invention is to provide a manually controlled hydraulically operated slide traversing movement. Another object of the invention is to provide a manually controlled, hydraulically actuated slide operating mechanism in which the speed of movement of the control member, such as a hand wheel, serves to control the rate of fluid pressure feeding movement. A further object of the invention is to provide a combined manually operable nut and screw feed and a hydraulic feed which are arranged so that rotation of the manually operable feeding wheel serves to actuate and control the position of a hydraulic control valve so that fluid under pressure serves to supplement the rotary movement of the feed screw and thereby to control the rate of infeeding movement of the grinding wheel. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing in which is shown one of various possible embodiments of the mechanical features of this invention,

Fig. 1 is a cross sectional view through a grinding machine, showing the improved wheel feeding mechanism, partly in elevation and partly in section;

Fig. 2 is a sectional view, on an enlarged scale, taken approximately on the line 2—2 of Fig. 1; and

Fig. 3 is a sectional view, taken approximately on the line 3—3 of Fig. 1, on an enlarged scale, showing the mechanism for actuating the control valve.

As illustrated in the drawing, a grinding machine is provided having a base 10 which is provided with a wheel slide 11 slidable transversely on suitable ways 12. A rotatable grinding wheel 13 is mounted on a wheel spindle 14 which is supported for rotation in suitable bearings (not shown) on the wheel slide 11. The grinding wheel 13 may be rotated from any suitable source of power, either by means of a driving belt from an overhead countershaft or it may be

driven from an electric motor either mounted within the base or on the wheel slide 11. A work piece 15 is rotatable on a headstock 16 and footstock (not shown) which are in turn supported on a longitudinally movable table 17. The table 17 is supported on a V-way 18 and a flat way 19 on the base 10 and serves to position the work piece 15 relative to the operative face of the grinding wheel 13.

To produce a relative feeding movement between the grinding wheel 13 and the work piece 15, a suitable feeding mechanism is provided which may comprise a half nut 23 depending from the wheel slide 11 and meshing with a rotatable cross feed screw 26 which is supported in 15 bearings 27 and 28, respectively, in the base 10. A manually operable feeding mechanism is provided comprising a manually operable micrometer feed wheel 29, such as that shown in the prior patent to Norton No. 762,838 dated June 14, 1904. Details of the micrometer adjustment of the feed mechanism have been omitted, since they are not considered part of the present invention. For further reference to detailed construction of the micrometer adjusting device, reference may be had to the above mentioned patent. The feed wheel 29 is rotatably mounted on a stud 30 which also supports a gear 31 meshing with a gear 32 mounted on the outer end of a rotatable shaft 33. The shaft 33 is supported in a suitable bearing 38 in the base 10, and is provided at its inner end with a pinion 36 which meshes with a gear 37 which is keyed on a reduced portion 38 of the rotatable cross feed screw 26. It will be readily apparent from the foregoing disclosure that rotation of the manually operable feed wheel 29 transmits motion through the gears 31, 32, 36 and 37 to rotate the cross feed screw and cause a relative approaching or receding movement between the work piece 15 and the grinding wheel 13. The mechanism above described serves manually to adjust the position of the grinding wheel relative to the work piece and may, if desired, be utilized to cause a grinding feed.

In the preferred construction, a suitable fluid pressure mechanism is provided which is arranged to move the slide 11 so as to cause either a rapid approaching or receding movement between the wheel and work and to cause a slow approaching movement during the grinding operation. This mechanism may comprise a fluid pressure cylinder 40 supported on the base 10 and having a piston 41 slidably mounted therein in axial alignment with the feed screw 26. The 45

piston 41 is mounted on a piston rod 42 which extends from each end of the piston and projects through each end of said cylinder. The rod 42 is connected at its inner end to the rear end of the feed screw 26. A slidably mounted member 45 is arranged to slide within a cylinder 46 and is slidably keyed thereto by means of a key 47. The slide 45 carries the bearing 28 which in turn supports the rear end of the feed screw 26, and the piston rod 42 is operatively connected to move the slide 45.

A fluid pressure system is provided including a reservoir 50 within the base 10 and a pump 51 which pumps fluid through a pipe 52 and a pipe 15 53, through a reversing valve 54, into the cylinder 40. A suitable relief valve 55 is provided in the pipe line 53 which is arranged so that excess pressure in the system will by-pass fluid through a pipe 56 into the reservoir 50.

20 The reversing valve 54, of the balanced piston type, is provided with a valve stem 57 which is controlled in a manner to be hereinafter described. In the position of the valve stem 57 (Fig. 1), fluid under pressure is admitted through 25 the reversing valve 54 into a cylinder chamber 60 to move the piston 41 and the feed screw 26 bodily toward the left (Fig. 1), and cause a rapid approaching movement of the grinding wheel 13 relative to the work piece 15. The parts illustrated in Fig. 1 are shown with the work and 30 wheel in grinding engagement with each other. During the approaching or infeeding movement, fluid is exhausted from a cylinder chamber 61, through the reverse valve 54, a pipe 62, into 35 the reservoir 50.

When it is desired to cause a rearward feeding movement of the grinding wheel 13 and the wheel slide 11, the valve stem 57 is shifted toward the right (Fig. 1) into its reverse position so as to cause the fluid under pressure 40 passing through the pipe 53 and valve 54 to enter the cylinder chamber 61 to cause a rearward movement of the grinding wheel 13.

It is desirable to provide a suitable mechanism 45 for reducing the rapid approaching movement of the grinding wheel to a slow grinding feed when the grinding wheel has been brought into engagement with the work piece. In the preferred construction, a secondary self-contained fluid pressure system is provided which, as illustrated, comprises a dash pot cylinder 65 having a dash pot piston 66 arranged in axial alignment with the feed screw 26, and preferably so constructed and arranged that the dash pot piston 66 is slidably mounted on an extended portion of the piston rod 42. When the wheel is fed toward the work, a rapid approaching movement is obtained until a sleeve 68, which surrounds the piston rod 42, engages the end of 50 the dash pot piston 66 and upon further movement serves to modify the approaching movement of the grinding wheel 13 so as to reduce the infeeding movement to a predetermined grinding feed. To facilitate adjustment of the 55 sleeve relative to the piston rod 42, an internal thread within the sleeve 68 engages a threaded portion 69 on the piston rod 42 and may be located in an adjusted position by means of a lock nut 70. A spring 71 within the dash pot piston 66 and surrounding the piston rod 42 serves to 60 return the dash pot piston to its initial or rearward position during the separating movement between the grinding wheel 13 and the work piece 15. During the idle return movement of the dash 65 pot piston 66, oil is drawn through a ball check

valve (not shown) into a dash pot chamber 72 from a self-contained reservoir 73 which is formed integral with the dash pot cylinder 65, so that the dash pot is then in condition for the next grinding operation.

The rearward or idle stroke of the dash pot piston 66 under the influence of the spring 70 is limited by a pin 75 which is fixed to the dash pot piston 66 and projecting through the dash pot cylinder head, and is arranged to engage an adjustable stop 76.

When the movement of the piston 41 starts to move the dash pot piston 66 toward the left (Fig. 1), the oil is forced from the dash pot chamber 72, through a needle valve 77, a port 78 and back 15 into the reservoir 73. The forward grinding feed continues until an adjustable stop sleeve 80 engages the end of the dash pot cylinders 65, thereby positively limiting the approaching movement between the grinding wheel 13 and the 20 work piece 15.

It is desirable to provide a suitable manual control for the valve 54 by which the fluid pressure system may be readily controlled so as to either operate independently of or in conjunction with the nut and screw mechanism above described, thereby providing a feeding mechanism for moving a massive machine tool slide with the minimum amount of exertion on the part of the operator. The gear 37 is provided with a projecting hub 90 and is slidably keyed to the portion 38 of the feed screw 26 and is arranged so that it may be thrown into or out of engagement with the pinion or gear 36 so that the feed screw 26 may be readily disconnected 30 from the hand wheel 29 in case it is desired to control the feeding movement of the grinding wheel by the fluid pressure mechanism above described.

It is desirable to provide a suitable connection between the manually operable hand wheel 29 and the fluid pressure control valve 54 so that when the hand wheel 29 is turned to cause a fluid pressure feeding of the slide, the slide will move either toward or from the work piece 40 45 at a rate determined by the speed of rotation of the hand wheel 29. The faster the hand wheel is rotated, the wider open will be the control valve 54. A rotatable sleeve 95 is rotatably mounted on the shaft 33. A collar 96 is fixed to the shaft 33 by means of a tapered pin 97, the collar 96 serving to locate the sleeve 95 on the shaft 33. A similar collar 98 is mounted on the shaft 33 and is slidably keyed thereto by means of a key 99. The collar 98 is preferably yieldably maintained in engagement with the other end of the sleeve 95. In order to hold the collar 98 in engagement with the end of the sleeve 95 with the desired frictional pressure, a spring 100 is provided surrounding the shaft 33 and interposed between the slidably mounted collar 98 and a collar 101 which is held in a fixed position on the shaft 33 by means of a tapered pin 102.

The spring 100 is of such a size, dimension, and compression as to provide sufficient frictional drive between the ends of the sleeve 95 and the collars 96 and 98, so that during the normal rotation of the shaft 33, the sleeve 95 rotates therewith.

The sleeve 95 is provided with a helical groove 103 on its outer peripheral surface. A sleeve 104 surrounds the periphery of the sleeve 95 and a pin 105 carried by the sleeve 104 engages the helical groove 103 so that when the shaft 33 and

sleeve 95 are rotated, the helical groove 103 and pin 105 serve to cause an endwise movement of the sleeve 104 relative to the sleeve 95. The sleeve 104 is provided with an elongated slot 84 (Fig. 2) which is operatively connected by means of a pin 85 to the short arm 106 of a bell crank lever 107. The bell crank lever 107 is pivotally mounted on a stud 108 carried by a bracket 109 which is fixed to the base 10. A long arm 110 of the bell crank 107 is connected by a stud 111 to one end of a rod 112. The rod 112 carries a stud 113 adjacent its opposite end which rotatably supports a gear 114. The gear 114 meshes with a rack bar 115 which is slidably supported in a portion 116 of the base 10. The rack bar 115 is connected to the end of the valve stem 57. A second rack bar 117 meshes with the upper portion of the gear 114 and is supported by a bracket 118 which is fixedly mounted to the sliding sleeve 45. Guide plates 120, 121, 122 and 123 serve to guide the gear 114 and to hold it against being displaced laterally from mesh with the rack bars 117 and 115 respectively.

In order that the feed screw 26 may be readily disconnected from the manually operable feed wheel 29 when desired, a yoked member 120 is pivotally mounted on a stud 121 which is fixed to the base 10. The upper end of the yoked member 120 is provided with opposed pins or studs (not shown) which ride in the groove in the hub 90 of gear 37. The yoked member 120 has a downwardly projecting arm 122 which is connected by a stud 123 with a rod 124. The rod 124 projects from the front of the machine base 35 and is connected at its outer end by a stud 125 carried by a manually operable control lever 126 which is pivotally mounted on a stud 127. The stud 127 is supported by a bracket 128 projecting from the front of the machine base. In 40 the full line position of the parts, as illustrated in Fig. 1 of the drawing, the gear 37 is out of mesh with the pinion 36. When it is desired to connect the manually operable hand wheel 29 to rotate the feed screw 26, the lever 126 is 45 shifted into the dotted line position 126a which serves through the link 124, the lever 122, and the yoked member 120 to slide the gear 37 in an endwise direction into mesh with the pinion 36.

In the operation of this mechanism, as illustrated in the drawing, when it is desired to cause an infeeding movement of the wheel slide 11 and the grinding wheel 13, the manually operable feed wheel 29 is rotated in a counter-clockwise direction (when facing the front of the machine) which serves to rotate the shaft 33 and the sleeve 95 in a clockwise direction which causes the pin 105 and the rod 112 to move towards the left (Fig. 1). The wheel slide being stationary, the rack bar 117 is also stationary since it is directly connected with the sleeve 45 which moves with the slide 11. The movement of the rod 112 towards the left (Fig. 1) serves to carry the stud 113 and gear 114 also in the same direction. The rack 117, being stationary, causes the gear 114 to roll on the rack 117 and thereby to cause an endwise movement of the rack 115 towards the left (Fig. 1) to move the valve stem 57 in the same direction so that the valve pistons assume the positions as illustrated in Fig. 1, so as to admit fluid under pressure to cause the piston 41 to move toward the left and thereby to produce an infeeding movement of the wheel slide 11 and grinding wheel 13. As soon as the piston 41 and the rack 75 117 start moving toward the left, thereby modi-

fying the movement of the gear 114, it tends to slow down the movement of the rack 115, and to move the valve stem 57 in the opposite direction. If, however, the manually operable hand feed wheel 29 is rotated at a uniform rate of speed 5 which serves to move the rack bar 115 slightly in excess of the feeding movement of the slide and wheel as well as the rack bar 117, the valve pistons are maintained in the position of the parts as illustrated. The speed of rotation of 10 the hand wheel 29 serves to govern the position of the valve pistons and thereby to control the rate of infeeding movement of the grinding wheel 13.

Similarly, on the reverse feeding movement of 15 the grinding wheel, that is to cause a separating movement of the wheel 13 and work piece 15, the feed wheel 29 is turned in the opposite direction which serves through the mechanism above described to shift the valve stem 57 so as to reverse the position of the valve pistons and admit fluid under pressure into the cylinder chamber 61 to cause a rearward movement of the grinding wheel 13 and the wheel slide 11.

If desired, the hydraulic feeding mechanism 25 may be operated in combination with the feed screw mechanism, in which case the operator shifts the control lever 126 into the dotted line position 126a to throw the gear 37 into mesh with the pinion 36 so that when the hand feed 30 wheel 29 is rotated to cause an infeeding movement of the grinding wheel, the feed screw 26 will be rotated and at the same time, through the mechanism above described, the control valve 54 will also be actuated to admit fluid under pressure into the cylinder chamber 60 so that the fluid pressure supplements the rotation of the feed screw in causing an infeeding movement of the grinding wheel.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. In a grinding machine, a rotatable grinding wheel, a transversely movable slide therefor, a fluid pressure piston and cylinder operatively connected to move said slide in either direction, a control valve to control the admission and exhaust of fluid to and from said cylinder, means including a pair of opposed racks and a gear therebetween, one of said racks being stationary and the other being connected to actuate said valve, and a manually operable control member movable in opposite directions to control said valve and arranged to move said gear longitudinally between said racks to actuate said valve whereby the control valve is actuated and the position thereof is controlled by the rate of rotation of said control member.

2. In a grinding machine, a base, a movable slide thereon, a fluid pressure piston and cylinder operatively connected to move said slide in either direction, a control valve to control the flow of fluid under pressure to and from said cylinder, a rotatable hand wheel, a cam which is arranged to be rotated thereby, a friction device 70 75

- interposed between the hand wheel and cam whereby the cam is frictionally rotated by the hand wheel, a rack bar arranged to actuate said control valve, a rack bar opposed thereto and movable with said piston, a gear interposed between said rack bars, a sleeve slidably supported on said cam, a follower on said sleeve which engages said cam, and connections between said sleeve and gear whereby the valve is actuated by and the position thereof is controlled by the rate of rotation of the hand wheel.
3. In a grinding machine, a base, a movable slide thereon, a fluid pressure piston and cylinder operatively connected to move said slide in either direction, a control valve to control the flow of fluid under pressure to and from said cylinder, a control member, a cam which is arranged to be rotated thereby, a friction device interposed between the control member and cam whereby the cam is frictionally rotated by the control member, a rack bar arranged to actuate said control valve, a rack bar opposed thereto and movable with said piston, a gear interposed between said rack bars, a sleeve slidably supported on said cam, a follower on said sleeve which engages said cam, and connections including a bell crank lever between said sleeve and gear whereby the valve is actuated by and the position thereof is controlled by the rate of movement of the control member.
4. In a grinding machine, a base, a movable slide thereon, a fluid pressure piston and cylinder operatively connected to move said slide in either direction, a control valve to control the flow of fluid under pressure to and from said cylinder, a rotatable hand wheel, a shaft rotatably mounted in the base and geared to said hand wheel, a rotatable sleeve on said shaft, a cam groove in the periphery of said sleeve, a friction device which is arranged normally to rotate said sleeve with said shaft, a second sleeve surrounding the first sleeve, a follower carried by said second sleeve which engages said cam, a bell crank lever pivotally mounted on said base and having one arm connected to said second sleeve, a rack bar connected to operate said valve, a rack bar opposed thereto which is moved by and in timed relation with said piston, a gear meshing with said rack bars, and connections between said gear and said bell crank lever whereby the control valve is actuated by and the position thereof is controlled by the rate of rotation of the hand wheel.
5. In a grinding machine, a base, a rotatable grinding wheel, a transversely movable slide therefor, a nut and screw feed mechanism interposed between the slide and base, a fluid pres-

sure piston and cylinder operatively connected to move said nut and screw axially in either direction, a control valve to control the admission and exhaust of fluid to and from the cylinder, a manually operable hand wheel, a shaft 5 rotated thereby, a pinion on the end of said shaft, a gear carried by said feed screw which is arranged to be meshed with said pinion, and connections between said shaft and said control valve whereby the feed screw is rotated and the 10 valve is actuated by and the position of the valve controlled by the rate of rotation of the hand wheel.

6. In a grinding machine, a base, a movable slide thereon, a nut and feed screw mechanism 15 to move said slide in either direction, a fluid pressure piston and cylinder operatively connected to move said screw axially in either direction, a control valve to control the flow of fluid under pressure to and from said cylinder, a 20 rotatable hand wheel, a shaft rotated thereby, a pinion formed on the inner end of said shaft, a gear slidably mounted on the end of said feed screw, a manually operable lever arranged to throw said gear into or out of mesh with said pinion so as to connect or disconnect the hand wheel with the feed screw, a rotatable cam carried by said shaft, a friction device carried by the shaft and arranged to rotate said cam, and 25 rack and gear connections interposed between 30 said cam and valve whereby the control valve is actuated by and the position thereof is controlled by the rotation of the hand wheel.

7. In a grinding machine, a base, a movable slide thereon, a nut and screw mechanism to 35 move said slide in either direction, a fluid pressure piston and cylinder operatively connected to move said slide in either direction, a control valve to control the flow of fluid under pressure to and from said cylinder, a rotatable hand 40 wheel, a shaft rotated thereby, a gear connection between said shaft and feed screw whereby the rotation of said wheel serves to rotate said feed screw to cause a movement of said slide, means including a manually operable lever to 4 connect or disconnect said gearing, a cam rotatably mounted on said shaft, a friction device arranged to hold said cam normally to rotate with said shaft, and rack and gear connections between said cam and said valve whereby rotation of said shaft serves to rotate said feed screw and to actuate said control valve so as to admit fluid under pressure to said cylinder and thereby modify the feeding movement of said slide produced by rotation of the nut and feed screw 5 mechanism.

WALLACE H. WOOD.
